UNITED STATES PATENT OFFICE.

HARRY M. BERRY, OF OIL CITY, PENNSYLVANIA.

CONTAINING AND DISPENSING ORGANIZATION FOR MOTOR OILS.

Application filed May 19, 1928. Serial No. 279,030.

This invention relates to an improved sealing-cover for use with drums in which lubricating oils, and more especially motor oils, are furnished to the user, such oils being sold by the manufacturer or refiner, largely to what are termed "filling stations", from which they are dispensed to automobile owners. The invention may also be appropriately termed a protective cover.

It will assist in the understanding of the object, purpose and utility of my improved cover, to first point out that certain lubricating oils, termed motor oils, have gained a world-wide reputation for lubricating quality, uniformity of specification, and purity under the insignia of "Guaranteed 100% pure Pennsylvania oil" which is the official insignia of the Pennsylvania Grade Crude Oil Association, and all refiners who are authorized to use this insignia upon their product, are obligated and required to keep their product up to a certain standard; a penalty is attached to the violation of that obligation. For this reason it becomes desirable to market this oil in such a way that it will not become adulterated, either accidentally or intentionally after it has left the refiner.

It is therefore the object of this invention to provide means whereby this grade of motor oil that is sold in and dispensed from drums may be more securely protected from adulteration, either accidental or intentional.

The construction whereby I am enabled to attain said object is clearly illustrated in the accompanying drawings in which:

Fig. 1 is a plan view of the head of a drum to which my improved cover is adapted to be attached.

Fig. 2 is a plan view of the top of my improved cover.

Fig. 3 is a central horizontal section of said cover.

Fig. 4 is a transverse section of the top of a drum with my improved cover, also shown in section, applied thereto, and with a dispensing pump in position for withdrawing oil from the drum.

Fig. 5 is a central transverse section of the head of a drum with the plugs or closure members removed from the ports.

The construction, application and utility of my improved cover will be best understood, if the construction of one commonly-used drum, to which said cover is adapted to be applied, is first set forth. These drums are usually constructed from sheet steel.

Referring, therefore, especially to Figs. 1 and 5, it will be noted that the form of the head 1 of said drum is such as is usually referred to as a "dished" head; the head 1 is surrounded by a chime or flange 2.

Said head is provided with two ports, 3 and 4; port 3 is usually utilized in filling the drum; the port 4 is adapted for the insertion of the suction pipe of a dispensing pump. Port 3 is provided with a closure member 5 and the port 4 is provided with a plug or closure member 6. These plugs are each secured in position by means of cooperating screw-threads upon the periphery of the plug and in the port walls. When motor oils are sold in these drums, from which it is to be dispensed by filling stations, many refiners who are operating under permit of the Pennsylvania Grade Crude Oil Association, take the precaution of sealing said plugs in the closed position before the drums leave the refinery. These drums are positioned vertically when in use.

It will be readily noted that, where the drum is provided with a dished head, as shown in the drawings, there is likelihood of water, foreign matter and impurities of various sorts finding lodgment in the dish of the head, and if the dispenser of the oil is not careful to properly clean the head, and in removing dirt, water, etc. that may be thereon before he removes the plug 6 from the pump-port for the insertion of the pump, said impurities may enter the drum upon the removal of said plug, thus destroying the purity of the oil, to such an extent that it does not conform to the requirements of said Pennsylvania Association, and its lubricating qualities are thereby impaired to some extent.

Furthermore, the threaded portion 7', dispensing pump 7, does not always fit leak-tight within the port 4, since the drum would not be properly vented for the withdrawal of oil therefrom if it did so, and because of this, I have provided an improved sealing-cover 8 which fits over the top of the drum, and effectively excludes any foreign matter from lodging upon or within the dish head of 1.

Said cover is preferably bumped, and provided with ports 9 and 10 for registry with the ports 3 and 4 respectively; the port 9 serves as an inspection port through which inspection may be made to ascertain whether the port 3 is properly closed, and the head of the barrel properly cleansed and free from water, etc. This port is provided with a cap or

closure 11, which may be removed, and replaced, and is preferably provided with a screw thread or other similar attaching device, as an interrupted thread 12; port 10 is 5 for the passage therethrough of the adjacent portion of the pump stock.

Said cover is provided with means, as 13 for the insertion of a sealing wire. Also the stock 10 of the pump 7 is provided at any suitable location with an eye as 14, for the insertion of a sealing wire as 15, which may be passed through said eyes, and its ends secured together by means of a suitable seal as 16, thus insuring the proper sealing of the drum and 15 the protection of its contents from adulteration as the oil is being dispensed therefrom.

Said ports 9 and 10 are surrounded by upwardly-extending flanges 18 and 19 respectively, the purpose of which is the exclusion of 20 water or impurities at the respective ports.

Said cover 1 rests upon the flange 2 of the drum and is somewhat larger in diameter than said drum to which it is applied, and its outer edge or periphery is formed into a downwardly-extending flange 20 which extends below the upper edge of flange 2 of the drum, whereby the cover structure provides effective exclusion to all deleterious matter which might otherwise find its way to the interior 30 of the drum.

The utility of my improved sealing-cover will be more readily appreciated when it is pointed out that much oil dispensing equipment of this type remains unhoused and out 35 in the open, beside dusty highways, and otherwise-exposed locations, where there is much liability of the contamination of oil if it is not carefully protected.

I claim the following:

40 1. A container and dispensing organization for motor oils and like liquids comprising in combination a vertically-disposed containing

drum for such liquids having an upper and a lower head, an internally screw-threaded pump-port in said upper head, a protective cover for said upper head seating upon the chime thereof, and having a pump port in registry with said port in said head; said cover port being provided with an upwardly-extending annular flange, a dispensing pump 45 having an externally-threaded portion for co-operation with the threads in said head port, whereby said pump is secured in its service position, also a member for contact and cooperation with said cover flange so as to effectually close said cover port and secure said cover in the service position, and securing means whereby the foregoing members are sealed in their service position.

2. A container and dispensing organization 60 for motor oils and like liquids comprising in combination, a vertically-disposed containing drum provided with suitable chimed heads and an internally screw-threaded port in the upper head, a protective cover for said upper head seating upon the chime thereof and in dirt-excluding contact therewith, also provided with a pump receiving port for registry with the pump port in said head, said cover port being provided with an upwardly-extending annular flange, a dispensing pump 65 having at the lower end of the stock an externally screw-threaded portion for co-operation with the screw-thread in said head port, also a means for co-operation and contact with 70 the upper edge of said flange whereby said cover-port is effectually closed and said cover rigidly secured to said drum when the pump is in its service position, and sealing means adapted to prevent and/or indicate the disarrangement of said members from their respective service and/or protective positions.

In testimony whereof I affix my signature.
HARRY M. BERRY.
